DEVICE FOR CLOSING CASEMENT WINDOWS

Filed July 17, 1930

Fig. 1.

UNITED STATES PATENT OFFICE

WALTER FREDERIC BROADWATER, OF ORLANDO, FLORIDA

DEVICE FOR CLOSING CASEMENT WINDOWS

Application filed July 17, 1930. Serial No. 468,721.

This invention relates to devices for closing casement windows. Where casement windows are constructed of wood, the warping of the wood through exposure to the weather makes the tight closing of such windows difficult. It is particularly difficult where the warping throws the upper swinging edge of the window outwardly as that part of the window is hard to reach and is not ordinarily fitted with any thing to grasp.

The object of the present invention is to provide a simple attachment readily applied to any casement window, which is neat in appearance, involves very few and very simple parts and is easy to operate even by children.

The invention consists of the novel arrangement, construction and combinations of parts hereinafter more particularly described.

20 One sheet of drawings accompanies this specification as part thereof, in which like parts are indicated by the same reference characters.

Figure 1 is a front elevation of a casement window showing the invention applied.

25 Figure 2 is a perspective of the principal operating lever.

Referring to the drawings 1 indicates the window, 2 the hinges on which the window is pivoted and 3 the window frame.

30 The window closing device comprises a rod 4 having two offset lever arms 5 and 6. The rod 4 is pivoted to the top frame member by straps 7 having bearings 8 in which rod 4 pivots. The lever arm 5 is positioned adjacent the swinging edge of the window and has its end turned inwardly into a hook part 20. The lever arm 6 is pivoted as at 9 to a vertical rod 10 the lower end of which is pivoted as at 11 to a lever 12 which is pivotally mounted on a side window frame part as by a pivot plate 13. Lever 12 is provided at its end with a hand grasp 14 and is held in adjusted position by a ratchet plate 15.

On the inner face of window 1 and at the upper swinging corner is positioned an eye member 17 which is preferably of angular shape to furnish an attachment plate and an inwardly directed part, the latter provided

with an eye opening 18 through which the hook 20 of lever arm 5 can engage.

In operation, the window being drawn partially to, and the outwardly warped upper swinging corner remaining out, lever 12 is raised until hook 20 reaches outwardly and engages the eye 18. Lever 12 is then depressed drawing lever arm 5 downwardly and closing the window snugly. When the window is closed lever 12 will be engaged with ratchet 15 to hold the window in its tightly closed position.

It will be particularly noted that the lever arms 5 and 6 are disposed with respect to each other so that when lever arm 5 is vertical lever arm 6 will be disposed at a slight angle to the vertical so that lever 6 cannot come into alignment with link 10. A spring 21 may be attached to lever 12, if desired to return the mechanism to inoperative position but ordinarily the weight of lever arm 5 can be adjusted to accomplish the same result.

Various modifications will readily suggest themselves to those skilled in the art but within the scope of the present invention as claimed.

Having thus fully described my invention I claim:

1. A sash closer comprising an eye member secured to the inner face of the sash near its swinging edge, a lever member pivoted to the window frame having a hooked arm adapted to engage the eye member, a second arm disposed at an acute angle to the first arm, a second lever pivoted to the window frame and a link connecting the second mentioned arm of the first lever and the second lever.

2. A device for closing an outwardly swinging casement window, comprising in combination with such window, an eye member positioned adjacent the upper, inner, swinging corner of the window, a bearing mounted at the corresponding corner of the window frame, a lever member mounted in the bearing having two depending arms arranged at an acute angle to each other, one of said arms having a hook formed on its free end adapted to engage the eye on the window a second lever mounted on the window frame a link

connecting said second lever and the second arm of the lever and means for adjustably securing said second lever.

In testimony whereof I hereby affix my signature.

WALTER FREDERIC BROADWATER.
